UNITED STATES PATENT OFFICE.

GEORGE W. WITHAM, OF PHILADELPHIA, PENNSYLVANIA, ASSIGNOR TO MACKELLAR, SMITHS & JORDAN, OF SAME PLACE.

DESIGN FOR FONT OF PRINTING-TYPES.

Specification forming part of Design No. 7,936, dated December 15, 1874; application filed December 4, 1874.
[Term of Patent 14 years.]

To all whom it may concern:

Be it known that I, GEORGE W. WITHAM, (assignor to MacKellar, Smiths & Jordan,) of the city and county of Philadelphia, Pennsylvania, have invented and originated a new and original Design for Font of Printing-Types, of which the following is a specification:

The nature of my design is clearly shown in the accompanying typographic impressions, to which reference is made; and consists in a black letter, formed as clearly shown in the said typographic impressions.

What I claim as new is—

The design for a font of printing-types, as shown.

GEO. WM. WITHAM.

In presence of—

C. F. HUCH,

GEO. MORLEY.
